CLAIM

The ornamental design for a switch housing for a perforating gun assembly, as shown and described.

DESCRIPTION

This application claims the benefit of U.S. Ser. No. 63/048,212 filed Jul. 6, 2020. That application is titled “Detonation System Having Sealed Explosive Initiation Assembly.”

FIG. 1 is a first perspective view of a switch housing for a perforating gun assembly, showing our new design.

FIG. 2 is second perspective view of the switch housing for a perforating gun assembly of FIG. 1, shown from a different angle.

FIG. 3 is a front plan view of the switch housing for a perforating gun assembly of FIGS. 1 and 2.

FIG. 4 is a rear plan view thereof.

FIG. 5 is a top plan view thereof.

FIG. 6 is a bottom plan view thereof.

FIG. 7 is a right side elevation view thereof; and,

FIG. 8 is a left side elevation view thereof.

The broken lines in the drawings depict portions of the switch housing for a perforating gun assembly that form no part of the claimed designs.
